UNITED STATES PATENT OFFICE.

JOHN A. LARRABEE, OF EAST MILTON, MASSACHUSETTS.

DESIGN FOR A PASTE-JAR.

No. 87,729.

Specification for Design.

Patented Dec. 12, 1905.

Application filed May 17, 1905. Serial No. 260,901. Term of patent 14 years.

To all whom it may concern:

Be it known that I, JOHN A. LARRABEE, of East Milton, in the county of Norfolk, and State of Massachusetts, have invented a new, original, and ornamental Design for Paste-Jars, of which the following is a specification.

The nature of my invention is fully shown in the accompanying drawing, which is a perspective view, looking from below, of a paste-jar embodying my design.

I claim—
The ornamental design for a paste-jar, as shown.

JOHN A. LARRABEE.

Witnesses:

C. F. BROWN,
E. BATCHELDER.
